CASTING MECHANISM FOR TYPOGRAPHS.

1,146,302.

Specification of Letters Patent. Patented July 13, 1915.

Application filed October 28, 1912. Serial No. 728,056.

To all whom it may concern:

Be it known that I, CLAIR H. BRASTED, a citizen of the United States, and a resident of Cleveland, county of Cuyahoga, and 5 State of Ohio, have invented a new and useful Improvement in Casting Mechanisms for Typographs, of which the following is a specification, the principle of the invention being herein explained and the 10 best mode in which I have contemplated applying that principle, so as to distinguish it from other inventions.

In casting mechanism for typographs the metal for forming the slug or line of type 15 is generally kept in a melting pot from which such metal is adapted to be supplied to the mold when occasion demands. To this end the pot is provided with a discharge spout through which the metal may thus be forced into the mold in the actual operation of casting. Naturally a tight fit requires to be made between the nozzle, that forms the end of this spout, and the face of the mold wherewith it is brought in contact and for this reason it is not only necessary that the surface of the parts in question be carefully machined so as to fit tightly together, but also that any particles of metal or other foreign matter should be 20 removed or wiped from said surfaces.

The object of the present invention is the provision of mechanism for thus wiping the nozzle of the casting pot, it being this part only that requires to be thus cared for in 25 the "Ludlow" typograph, to which the casting mechanism illustrated more particularly pertains. In such "Ludlow" typograph a plurality of matrix bars are employed, such bars being longitudinally arranged in a 30 trough and normally freely movable over a casting slot in such trough, so that by suitably composing, or distributing, said bars to bring over such slot any desired series of characters, a matrix for a type line, the 35 width of a column of printed matter, is formed. In the approved constructional form of such typograph, the trough, and thus the mold which co-operates with the aforesaid slot in the casting operation, are 40 disposed horizontally, and the casting pot 45 is brought with its nozzle against the under

side of said mold. The general features of construction just set forth of course form no part of the present invention, the latter consisting of the means hereinafter fully 55 described and particularly set forth in the claims.

The annexed drawing and the following description set forth in detail certain mechanism embodying the invention, such disclosed means constituting, however, but one of various mechanical forms in which the principle of the invention may be used.

In said annexed drawing, Figure 1 is a 60 plan view of the casting mechanism of a typograph of the kind above referred to, showing my present improvements associated therewith; Fig. 2 is a sectional view of a detail on the line 2—2, Fig. 3; while Figs. 70 3 and 4 are broken plan views, respectively illustrating in different operative positions, the parts that appear in Fig. 1.

The mold 1, over which the matrix bars (not shown) are assembled, appears stripped of its associated parts, whereby it is adapted to be variously positioned incidentally to the discharge therefrom of the slug and the trimming of the latter. Similarly, the actuating mechanism for the casting pot 2, which is designed to co-operate with the slot 3 in 75 said mold in order to supply thereto the molten metal for forming the slug, has been omitted. For the present purpose such pot may be regarded as having simply an oscillatory movement in a horizontal plane from the 80 position of rest illustrated in full lines in Fig. 1 to the operative position illustrated in dotted lines in the same figure. Said pot is further given either a translatory, or oscillatory, movement in a vertical plane as well, in order that its discharge nozzle 4, after being 85 thus first brought directly beneath the mold, may then be elevated into close connection therewith. The detailed construction of the pot may, moreover, be disregarded, other than to note that it is provided with a reciprocable piston, or plunger 5, which is 90 suitably actuated in the registering position of the nozzle just referred to, to force the molten metal from the body of the pot 100 through the spout 4 and into the mold.

For the purpose of wiping the face of

2
 the nozzle, or squirt plate 5, where such a plate closes the end of the nozzle, I pivotally mount a member 6 on a bracket 7 extending inwardly from the machine frame 5 to a point adjacent to the path of travel of the spout. This member is furnished on its under side with a pad 8 of fabric, which may be of heat resisting material as asbestos, although ordinary cloth, if of strong 10 enough texture, is preferably used, the quickness of the movement rendering this possible. The relative elevation of the pot nozzle and said member is such that, upon oscillation of the latter, the pad carried 15 thereby will brush across the end of the nozzle.

Normally a tension spring 10 retains said member 6 in the inoperative position shown in Fig. 1, but an arm 11 carried by the pot 20 is disposed so as to engage a shoulder 12 on the under side of said member and closely adjacent to its pivotal axis so as to swing said member inwardly and thus across the nozzle, upon movement of the spout toward 25 the mold. By reason of the shoulder being thus closely located to the pivotal axis of the member, the movement just described is a very rapid one, being almost instantaneous, as is also the return of the member across 30 the nozzle when the arm releases said member, as it does, immediately following the position of parts illustrated in Fig. 4, under compulsion of the spring 10. A double wiping movement is accordingly secured, and 35 that entirely automatically, incidentally to the movement of the spout of the casting pot. A stop 13 serves to receive the impact of the member 6 upon its return to inoperative position, while a second, leaf spring 14 40 serves to guide the arm 11 into engagement with the shoulder 12 on the under side of said member.

The general mode of operation of the device has been indicated, it is believed, with 45 sufficient fullness in the preceding description of its construction. It will be understood, of course, that the device is not limited in its application to the specific form of typograph hereinbefore referred to, but 50 may be used with others wherein a corresponding relation and movement of parts is found; furthermore, by a simple extension of the arm 6, such arm, or a duplicate thereof, may be readily adapted for wiping the 55 under face of the mold 1, instead of the upper face of the squirt plate 5. It should further be noted that the wiping movement of the arm 6 occurs just previously to the casting operation. There is hence no chance 60 for the metal to chill in the nozzle after such wiping, or for dirt to collect on its face.

Other modes of applying the principle of my invention may be employed instead of the one explained, change being made as

regards the mechanism herein disclosed, 65 provided the means stated by any of the following claims or the equivalent of such stated means be employed.

I therefore particularly point out and 70 distinctly claim as my invention:—

1. In mechanism of the class described, the combination of a slug-casting mold; a movably mounted pot for molten metal having a spout adapted, in one position of said pot, to register with said mold; a member 75 movably mounted adjacent to the path of travel of such spout and adapted to wipe the same; means normally retaining said member in inoperative position; and an arm carried by said pot and adapted to engage 80 said member, the effect of such engagement being to move said member across such spout.

2. In mechanism of the class described, the combination of a slug-casting mold; a 85 movably mounted pot for molten metal having a spout adapted, in one position of said pot, to register with said mold; a member movably mounted adjacent to the path of travel of such spout and adapted to wipe 90 the same; a spring normally retaining said member in inoperative position; and an arm carried by said pot and adapted, upon movement of the latter, to temporarily operatively engage said member and then to release the same, the effect of such engagement being to move said member across such spout in one direction, and said spring being effective, upon release of said member, to move the same across such spout in the 95 opposite direction.

3. In mechanism of the class described, the combination of a slug-casting mold; a movably mounted pot for molten metal having a spout adapted, in one position of said 100 pot, to register with said mold; a member pivotally mounted adjacent to the path of travel of such spout and adapted to wipe the same; a spring normally retaining said member in inoperative position; and an arm 11 carried by said pot and disposed to engage said member during a portion of the movement of said pot and thereupon release said member, the effect of such engagement being to move said member across such spout 11 in one direction, and said spring being effective, upon release of said member, to move the same across such spout in the opposite direction.

4. In mechanism of the class described, 12 the combination of a slug-casting mold; an oscillatorily mounted pot for molten metal having a spout adapted, in one position of said pot, to register with said mold; a member pivotally mounted adjacent to the path 12 of travel of such spout to wipe the same; a spring normally retaining said member in inoperative position; and an arm carried

by said pot and disposed to engage said member at a point near its pivotal axis during a portion of the movement of said pot and thereupon release said member, the effect of such engagement being to swing said

lease of said member, to move the same across such spout in the opposite direction.

Signed by me this 25 day of October, 1912.

CLAIR H. BRASTED.
